UNITED STATES PATENT OFFICE.

TERESA I. L. BUTTS, OF ALBUQUERQUE, NEW MEXICO.

THREAD CUTTING AND HOLDING ATTACHMENT FOR SPOOLS.

1,044,014.

Specification of Letters Patent.

Patented Nov. 12, 1912.

Application filed August 17, 1912. Serial No. 715,627.

To all whom it may concern:

Be it known that I, **TERESA ISABEL L. BUTTS**, a citizen of the United States, residing at Albuquerque, in the county of Bernalillo and State of New Mexico, have invented certain new and useful Improvements in Thread Cutting and Holding Attachments for Spools, of which the following is a specification, reference being had to the accompanying drawings.

This invention relates to improvements in thread cutting and holding attachments for spools and has for its primary object to provide a simple device for this purpose which may be cheaply manufactured and is of great convenience and serviceability in practical use.

Another and more specific object of the invention is to provide a thread holding and cutting attachment formed from a single length of spring metal and adapted for insertion into the opening of the spool, the said device being so formed as to preclude liability of its accidental or unintentional displacement from its operative position with relation to the spool.

A still further object of the invention is to provide a device of the above character which may be manufactured in large quantities at comparatively small cost and is very durable as well as extremely efficient and serviceable in actual use.

With the above and other objects in view as will become apparent as the description proceeds, the invention consists in certain constructions, combinations and arrangements of the parts that I shall hereinafter fully describe and claim.

For a full understanding of the invention, reference is to be had to the following description and accompanying drawing, in which—

Figure 1 is a perspective view of a spool showing my improved attachment applied thereto, and the thread held upon the end of the spool; Fig. 2 is a longitudinal section through the spool; and Fig. 3 is an enlarged perspective view of the attachment removed from the spool.

Referring in detail to the drawing 5 designates the ordinary wooden spool upon which the thread is wound. This spool is provided with the usual central longitudinal opening or bore 6.

My improved attachment which is designed for application to the spool is con-

structed from a single length of flat spring metal indicated generally by the numeral 7, bent upon itself intermediate of its ends, as shown at 8 to provide normally divergently disposed arms 9 and 10, respectively, the arm 10 being somewhat greater in length than the arm 9. The end of the shorter arm 9 of the metal strip is bent inwardly toward the longer arm 10 as indicated at 11. The outer end portion of the longer arm 10 is also bent at right angles to the main portion thereof but in an opposite direction to the end 11 of the arm 9 as shown at 12. This laterally extending end 12 of the longer arm 10 normally extends to a slight distance beyond the end of the arm 9 and the extremity thereof is reversely bent as shown at 13 to provide closely engaged portions between which the thread is adapted to be disposed as will be more clearly described in the following description of the use of the attachment. The extreme end of the portion 12 of the arm 10 is again extended outwardly and is upwardly bent from the reverse bend 13 thereof as shown at 14. This upwardly extending extremity is provided with a notch 15 the edges of which are sharpened.

In the use of my improved attachment, the diverging arms 9 and 10 thereof are inserted into the opening 6 of the spool 5 and forced into said opening until the bent end 11 of the arm 9 is disposed inwardly of the end face of the spool. In this inward movement of the resilient arms 9 and 10 of the device into the opening 6 in the spool, the angular end 11 of the arm 9 is gradually forced laterally into engagement with the arm 10 so that when the device is disposed in its proper position in the spool, the bearing engagement of said angular end of the arm 9 against the arm 10 will force the latter arm into close frictional contact with the wall of the opening 6. It will thus be apparent that the device is retained in its proper position in the spool opening against liability of its accidental longitudinal movement. The laterally extending end portion 12 of the arm 10 projects outwardly from the opening 6 over the end face of the spool so that the reverse bend 13 in the portion 12 is located contiguous to the edge of the spool. After a desired length of thread has been unwound from the spool, the thread is passed over the end of the spool and moved into the lapped or reversely bent portion 13 of the holder where it is held against fur-

ther unwinding. The thread is now engaged in the notch 15 and severed by forcing the same against the sharpened edges thereof. In this manner the thread may be very 5 easily and quickly cut after the desired portion has been removed from the spool. The end of the thread remaining thereon is securely held so that the thread will not become unwound.

10 From the foregoing it is believed that the construction and manner of use of my improved spool attachment will be clearly understood.

15 The device may be easily and quickly attached to or removed from the spool, and provides convenient means, which is always at hand, whereby the thread may be easily and quickly severed and held upon the spool to prevent unwinding of the same.

20 Owing to the fact that the entire device is formed from a single length of metal which may be stamped out by means of a die and readily bent into the desired form, it will be apparent that the invention can be manufactured in large quantities at very small 25 cost.

25 The attachment is preferably constructed of spring metal, but it will be obvious that other material which is capable of accomplishing the desired results may be employed. The invention is, of course, also susceptible of other modifications in form and proportion without departing from the 30 essential features or sacrificing any of the advantages thereof.

35 Having thus described the invention what is claimed is:

1. A thread cutting and holding attachment for spools comprising a single strip of 40 spring metal bent intermediate of its ends to provide divergently disposed arms which

differ in length, the said arms being adapted for insertion into the opening of a spool, the longer arm having its end portion offset for engagement upon the end face of the spool 45 and provided with a reverse bend for clamping engagement with the thread, the extremity of said offset end of the arm being provided with a V-shaped notch having sharpened edges, substantially as and for the purpose specified.

2. A thread holding and cutting attachment for spools comprising a single strip of spring metal bent upon itself intermediate of its ends to provide divergent resilient 55 arms, one of said arms being longer than the other and provided at its end with a laterally disposed portion, the extremity of said lateral portion of the arm being reversely bent to provide a clamp for holding the end 60 of the thread, the extremity of said arm being extended outwardly from the reverse bend therein and provided with a V-shaped notch having sharpened edges, said laterally disposed portion of the arm being adapted 65 for close engagement with the end face of the spool and extending from the opening therein to the outer edge of the spool, said shorter resilient arm extending entirely 70 within the opening of the spool and having its extremity angularly bent and adapted for bearing engagement against the longer arm to force the latter arm into close frictional contact with the wall of the spool opening when the attachment is in position 75 therein.

In testimony whereof I hereunto affix my signature in the presence of two witnesses.

THERESA I. L. BUTTS.
